(57) **CLAIM**

The ornamental design for a synthetic resin pipe, as shown and described.

DESCRIPTION

FIG. 1 is a front view of a synthetic resin pipe showing my new design;

FIG. 2 is an enlarged front view thereof;

FIG. 3 is an enlarged top plan view thereof;

FIG. 4 is a left side view thereof;

FIG. 5 is a right side view thereof;

FIG. 6 is a cross sectional view taken along line 6—6 of FIGS. 2 and 4;

FIG. 7 is a cross sectional view taken along line 7—7 of FIG. 4;

FIG. 8 is a cross sectional view taken along line 8—8 of FIG. 2;

FIG. 9 is a cross sectional view taken along line 9—9 of FIG. 2;

FIG. 10 is a right side perspective view of the synthetic resin pipe showing my new design; and,

FIG. 11 is a left side perspective view thereof.

A rear view is omitted since it is a mirror image of the front view.

A bottom plan view is omitted since it is a mirror image of the top plan view.

Each of the views of FIGS. 1—3, 6, 7, 10 and 11 includes separation lines to indicate that, for ease of illustration, the precise length of the synthetic resin pipe is not claimed. Portions omitted from between the separation lines continue sequentially in the same pattern as established in FIG. 1 between the two sets of separation lines.
